WRAPPING MACHINE

Wilhelm E. Bronander, Montclair, N. J.

Application June 27, 1936, Serial No. 87,638

2 Claims.

(Cl. 93—2)

This invention relates to wrapping machines.

The invention has for its salient object to provide a machine for wrapping articles that is simple and practical in construction, comprises few parts and will effectively and efficiently wrap the articles or packages.

Another object of the invention is to provide a machine of the character described with simple, practical and effective means for applying adhesive to the parts to be joined or secured or for moistening or applying solvent to said parts if the wrapper is formed of material such as coated regenerated cellulose film commercial known under the trade-mark "Cellophane".

Further objects of the invention will appear from the following specification taken in connection with the drawings which form a part of this application, and in which

Fig. 1 is a top plan view of a machine constructed in accordance with the invention;

Fig. 2 is a longitudinal sectional elevation of the machine shown in Fig. 1;

Fig. 3 is a longitudinal sectional elevation taken substantially on line 3—3 of Fig. 1;

Fig. 4 is an enlarged detail sectional elevation of the mechanism for applying the adhesive to the longitudinal folds of the wrapper;

Fig. 5 is a detail plan view of the adhesive applying means, somewhat diagrammatic; and

Figs. 6 to 11, inclusive, are perspective views illustrating the wrapper and article at various successive stages in the wrapping operation.

The invention briefly described consists of a wrapping machine comprising means for feeding an article to be wrapped, means for feeding a wrapper strip across the path of movement of the article and for severing the strip to form wrapper lengths, means for moistening or applying adhesive to portions of the wrapper during its movement through the wrapping and folding mechanism and means for folding and securing the wrapper around the article. The wrapper and article are fed by successively acting feeding means to and through the folding means which

folds the wrapper around the top, one end and the bottom of the article and folds the side flaps across the sides of the article, adhesive being applied to the inner side flap prior to the folding of the outer side flap thereover. After the wrapper has been so folded the ends of the wrapper will project beyond one end of the article in the form of an open ended tubular extension.

At this stage the machine operator tucks the ends of the wrapper against the end of the article and the article and wrapper are placed on

a third support which is disposed below the level of the plane of the support or supports upon which the article and wrapper have previously been fed. In this manner the bottom end flap is folded upwardly against the end of the article leaving the upper end flap projecting in the plane of the upper surface of the wrapper. The article and wrapper are then fed through the final folding mechanism by endless feeding means and the final or upper end fold is folded downwardly against the lower end fold. Prior to this last folding operation the outer surface of the folded end flap has applied thereto adhesive or solvent.

Further details of the invention will appear from the following description.

In the form of the invention particularly illustrated in the drawings there is shown a machine comprising three supports or supporting tables A, B and C, the supports A and B being disposed in the same plane and the support C being disposed in a plane located below the level of the plane in which the supports A and B are located and furthermore being disposed at right angles to the supports A and B.

The support A has formed therein a slot or opening 20 through which a wrapper strip S is fed from a supply roll 21 by feed rolls 22 and 23. Cuttings mechanism consisting of a rotary knife 24 and a stationary knife 25 severs the strip into wrapper lengths.

The articles X to be wrapped are fed from a hopper H by feed bars or rods 27 carried by a pair of endless feeding members 28 and 29. The articles are fed along the support A and engage the wrapper strip S which has previously been fed through the slot 20 across the path of movement of the articles. The articles are fed by the members 27 beneath a top plate 30 disposed above the support A in advance of the slot 20, the strip being folded around the advance end of the article and across the upper and lower surfaces thereof in the manner shown in Fig. 2. After the article and wrapper have been fed beneath the top plate 30 the cutting mechanism operates to cut the strip and the free ends of the wrapper length will extend rearwardly from the rear edge of the article.

The article and wrapper are fed from the support A to the support B by the transverse feeding members 27 and are fed along the support B by feeding lugs or members 35 carried by an endless feeding member 36 supported on sprockets 37 and 38. The feeding members 27 pass downwardly through an opening 39 disposed between the supports A and B and move out of engagement

with the rear edges of the articles as the feeding members 35 move into engagement therewith.

Any suitable driving connections may be provided for the feeding members above described, but in the form of the invention shown the endless feeding members or chains 28 and 29 are carried by sprockets 40 and 41 at the rear ends of the feeding members and by sprockets 42 and 43 at the front ends thereof. The sprockets 42 and 43 are mounted on a shaft 44 on which is also mounted a sprocket 45 which is driven by a chain 46 from any suitable source of power.

The shaft 44 also has secured thereto a gear 47 which meshes with a gear 48 mounted on a shaft 15 49 on which the sprocket 31 is mounted.

The shaft 49 also has secured thereto a sprocket 50 which is connected by a chain 51 to drive a sprocket 52 mounted on a shaft 53 which carries the rotary cutter 24. Shaft 53 has also secured thereto a gear 55 which meshes with an idler gear 56 which in turn meshes with a gear 57 mounted on a shaft 58 which carries the feed roll 23. Gear 57 also meshes with a gear 59 carried by a shaft 60 on which is mounted the feed roll 22.

Side walls 65 and 66 are mounted on the support B and are provided with stationary tuckers 67 and 68 at the entrance ends thereof to tuck the front end tucks 70 formed in the wrapper. The side walls also have slots 71, 72 and 73 which function in the usual manner to fold the inner side folds 75 downwardly and the outer side folds 76 upwardly and inwardly against the folds 75. The folding slots have not been illustrated in detail since they are old and common in the wrapping art.

After the tucks 70 have been formed in the advance ends of the wrapper the folds 75 are folded downwardly against the sides of the wrapper by the slots 71. The article and wrapper at this stage in the folding operation are shown in Fig. 6. When the article and wrapper have reached this stage and have reached the point indicated at Y in Fig. 2 adhesive or solvent is applied to the lower margins of the folds 75, as shown in Fig. 7. This is accomplished by means of the adhesive applying means particularly illustrated in Figs. 4 and 5.

The adhesive applying means consists of rotary disks 80 formed of felt or other suitable absorbent material. The disks 80 are supported on rotating heads 81 disposed at the upper ends of spindles 82 mounted at their lower ends on ball thrust bearings 83. The spindles are freely rotatable and are not positively driven. The disks 80 are secured to the heads 81 in any suitable manner, as by flat rings 84. Screws extend through the rings and disks and are secured to the heads 81.

The spindles 82 are mounted in journals 85 carried by arms 86 pivoted at 87 to lugs 88. Springs 89 are secured at their inner ends to a frame or support 90 and at their outer ends to the arms 86, the springs exerting a force tending to hold the arms and disks inwardly, thus forcing the peripheries of the felt disks 80 against the longitudinal edges of the folds 75. The walls 65 and 66 are recessed, as shown at 91, to receive the peripheral portions of the felt disks 80.

Adhesive is fed to the disks 80 from receptacles R by gravity, the receptacles being provided with downwardly extending outlet conduits 92 controlled by needle valves 93.

After adhesive has been applied, as shown in Fig. 7, to the lower outer edges of the folds 75,

the bottom or outer side folds 76 are folded upwardly by the action of the slots 73 and the article and wrapper then take the form shown in Fig. 8 in which it will be seen that the wrapper has been wrapped around the end, top, bottom and sides of the article, the free ends of the wrapper projecting rearwardly to form an open ended tubular extension. The wrapper has reached the form shown in Fig. 8 at position Z in Fig. 2.

After the wrapper has been wrapped around the article in the manner shown in Fig. 8 the operator of the machine folds the two ends of extension shown at 95 and 96 inwardly against the end of the article and places the article and wrapper on the support C which, as above explained, is disposed below the level of the supports A and B. As the package is placed on the support C the bottom end fold 97 will be folded upwardly in the manner shown in Fig. 9 against the rear end of the article. This leaves the upper end fold 98 projecting rearwardly substantially in alignment with the upper surface of the article and wrapper. The package is then engaged on the support C by one of a series of feeding members or lugs 100 carried by an endless chain 101 supported on sprockets 102 and 103 mounted on shafts 104 and 105. The shaft 104 has secured to its rear end a worm wheel 106 which meshes with a worm gear 107 mounted on the shaft 44.

A wall 110 forms the guide for one side of the package, the other side being guided by a wall 111, the latter wall being provided with a slot 112 which engages the upper end flap 98 and folds this end flap downwardly against the inner end flap 97. The wall 111 has formed therein a slot 115 which receives the periphery of an adhesive applying disk 116 similar to the disks 80 shown in Fig. 4. The disks 116 is freely rotatable and engages and applies adhesive to the outer surface of the bottom end fold 97, as shown in Fig. 10. After the adhesive or solvent has been applied thereto in the manner shown in Fig. 10, the upper or outer end fold 98 is folded downwardly by the action of the slot 112 and the wrapping of the article is completed.

From the foregoing description the operation of the machine will be clear, but it may be briefly summarized as follows: The article and wrapper are first fed along the support A on which the wrapper is fed around the end and across the top and bottom of the article. From the support A the articles are fed along the support B by the feeding members 35 and during this movement the upper side folds 75 are folded downwardly and inwardly against the sides of the article after the tucks 70 have been formed therein. This stage in the operation is shown in Fig. 6. The rotary adhesive applying disks 80 then engage the lower outer margins of the folds 75 and apply adhesive or solvent thereto and thereafter the further movement of the article and wrapper along the support B will cause the outer side folds 76 to be folded upwardly and inwardly against the fold 75. This stage in the operation is shown in Fig. 8.

The operator of the machine then, by manual operation, folds the end tucks 95 and 96 inwardly against the ends of the article and places the article and wrapper on the support C. This last operation causes the bottom end folds 97 to be folded upwardly and inwardly against the end of the article leaving the upper end fold 97 projecting outwardly in the manner shown in Fig. 9.

The article and wrapper are then fed along the support C and the upper outer margin of the fold 97 receives adhesive from the adhesive applying disk 116. The final fold is then made by the 5 movement of the article and wrapper along the support C causing the upper end fold 98 to be folded downwardly against the fold 97 by the slot 112.

It will be evident from the foregoing description that a simple, practical and effective machine 10 has been designed for wrapping and sealing articles.

Although one specific embodiment of the invention has been particularly shown and described it will be understood that the invention is 15 capable of modification and that changes in the construction and in the arrangement of the various cooperating parts may be made without departing from the spirit or scope of the invention, 20 as expressed in the following claims.

What I claim is:

1. The method of wrapping an article which consists of feeding an article and wrapper in a predetermined path of movement, and during 25 such movement folding the wrapper around the bottom, advance end and top of the article, tucking the advance end of the wrapper projecting beyond the sides of the article against the front

end portions of said sides and folding the wrapper against the sides of the article, leaving the ends of the wrapper projecting beyond the rear end of the article, manually tucking the ends of the projecting portion of the wrapper against the rear end of the article, transferring the article and wrapper to a path of movement and during such transfer folding upwardly the lower fold of the projecting portion of the wrapper at an angle to the first path of movement, feeding the article 10 and wrapper in said second path of movement and during such movement folding the end upper fold against the rear end of the article and wrapper.

2. In a wrapping machine, a support having 15 side walls arranged to receive therebetween a partially wrapped article in which the wrapper has been folded around the top, bottom, one end and sides of the article, leaving the ends of the wrapper projecting rearwardly of the rear end of 20 the article, one wall being arranged to engage the closed end of the package and the other wall being adapted to engage and fold up a bottom projecting portion of the wrapper, means for feeding the article and wrapper along said support, 25 and means for folding the top projecting portion of the wrapper against the bottom folded portion.

WILHELM B. BRONANDER.
